BRACELET ATTACHMENT

Albert B. Goulden, Los Angeles, Calif.

Application July 31, 1937, Serial No. 156,725

4 Claims. (Cl. 24—71)

This invention relates to a bracelet attachment, and more particularly to an improved means for releasably latching or locking an extensible bracelet in its contracted condition.

5 Among the objects of the invention are: to provide a quicker acting and more satisfactorily operable release which, upon its manual operation, will automatically extend the diameter or compass of the bracelet sufficiently to permit it

10 to pass over the hand of the wearer; to provide an improved spring-impelled extending means for the bracelet; to provide an improved arrangement of cooperating slidable and folding members which form a portion of the circumferential extent of the bracelet; to furnish a finger-nail-operable release element which is operable by less force and hence will safeguard breaking the nails of the operator; to furnish opening and closing means for the bracelet which will operate with less frictional resistance; to furnish an extension spring which, while operating efficiently, will not materially thicken the bracelet; and to, in general, improve upon extensible bracelets with regard to simplicity of construction and dependability of operation.

25 Other objects, advantages and features of invention will hereinafter appear.

Referring to the accompanying drawing, which illustrates what it at present deemed to be a preferred embodiment of the invention, now reduced to practice:

Fig. 1 is a side elevation of the casing of the extensible connecting unit.

Fig. 2 is a cross section on line 2—2 of Fig. 1.

35 Fig. 3 is a cross section on line 3—3 of Fig. 7.

Fig. 4 is an end elevation of the member shown in Fig. 1, looking from right to left as indicated by the line and arrows in the latter view.

Fig. 5 is a side elevation of the finger-nail-operable releasing member, separately shown.

40 Fig. 6 is an elevation of said releasing member looking at the right end thereof as viewed in Fig. 5.

Fig. 7 is a view partly in side elevation and partly in longitudinal mid section of the complete connecting unit or assembly, showing said unit in both the unfolded and longitudinally extended condition.

Fig. 8 is a plan view of a bracelet furnished 45 with the connecting unit provided by the invention, said unit being shown in the folded up and non-extended condition with an extended chain section of the bracelet attached to each end thereof.

50 Fig. 9 is a perspective view of the non-swing-

able member of the three-part foldable extension.

Fig. 10 is a plan view of the middle member or link of the foldable extension.

Fig. 11 is a side elevation of the middle member or link of the foldable extension.

Fig. 12 is a plan view of the terminal member of the foldable extension of the connecting assembly.

Fig. 13 is a cross section on line 13—13 of 10 Fig. 12.

Fig. 14 is a plan view of the flatly coiled compression spring which automatically extends the connecting assembly whenever the latching element thereof is released.

Fig. 15 is a cross section on line 15—15 of 15 Fig. 14.

Referring in detail to the drawing, the connecting assembly 5 (see Fig. 8) provided by this invention may be used to connect to each other 20 a pair of bracelet sections 6 for wrist watches or the like, the particular kind of bracelet sections used not pertaining to the invention.

The casing 7 of the connecting unit or assembly, the slidable, non-folding bed plate member 8, the middle foldable member 9 and the terminal foldable member 10 are all uniformly arched to a slight extent in order that said members 9 and 10 in their folded up condition may be nested within said bed plate 8 and the assembly 30 of parts 8, 9 and 10 in turn nested within the casing 7. Said casing 7 is substantially rectangular in cross section except that, along the mid-width of its convex face it is furnished for nearly its entire length with a rise or flat bead 7b that 35 aids in housing the resilient releasing tongue 11 of the latching or locking means. One end portion 12 of said tongue is doubled over upon itself in an angular manner to form a smooth and substantial finger nail hold for the operator to use 40 in prying up on that end of said tongue to effect the release of the pawl tooth 12a carried thereby, the purpose of which will presently appear.

The opposite end portion of the resilient tongue 11 is furnished with a plurality of notches 13, one 45 of said notches forming a seat for the edge portion of a lip 14 formed by an end flange of the inner wall 15 of the casing 7, the tongue 11 thus being retained pre-stressed in its operative position within said casing, whereby the free end 50 thereof may be flexed. The purpose of providing two or more of the notches 13 is in order to facilitate the insertion of the spring tongue 11 to the correct operative position.

The slidable member 8 is of a channel shape 55

in cross section and has at its inner end a head 20 which fits slidably within the casing 7 below the inserted latch tongue 11, the insertion of said member 8 being opposed by a compression spring 5 21 which is coiled in a flatwise manner to fit within said casing alongside said tongue. Adjacent to its inner end the casing 7 has internal pins 7x which cooperate with the head 20 to prevent a complete withdrawal of the slidable member 8 from said casing. The head 20 is shown made up of the end flange shown and of a shouldered projection 20s at each side thereof, said projections engaging said pins to limit the outward slide of said member 8.

15 A pivot 22 connects the outer end of member 8 with the middle member or link 9 of the three part foldover extension, and a pivot 23 connects said member 9 with the terminal member 10. The terminal member 10, shown in cross section 20 in Fig. 13, is of a channel shape, but has a broad longitudinal depression 24, along its mid-width, and when members 8, 9 and 10 are in their folded over inserted position within the casing 7, said depression 24 then forms a track or runway for 25 the spring tongue 11. Along this depression 24 travels the tooth 12a of said tongue and in this depression are a series of triangular apertures 25 each of which has a straight side constituting a ratchet shoulder or ratchet tooth which 30 operates with the pawl tooth 12a of the tongue 11 to retain the three-part foldover extension in a more or less retracted position in opposition to the spring 21.

Inside of the casing 7, at each side of the channel under its longitudinal bead 7b, is stationed a short keeper pin 26, and when the tongue 11 is properly inserted these pins hold its mid-length portion snugly into contact with the inner face of the rise 7b and also prevent lateral displacement of said tongue. Said tongue is resilient and is given a normal curvature sufficient to impart the desired amount of spring action to its pawl portion 12a.

The outer wall of the casing 7 is furnished at 45 the closed end of said casing with a hooked extension 30 to be hooked onto the bracelet section 6 at that end of said casing. The free end of the terminal foldover member 10 is shown curled at 50 31 for the purpose of connecting it with the other bracelet section.

In the operation of the device, in order to contract the foldover assembly from its extended condition shown in Fig. 7, the terminal members 9 and 10 are first folded back upon the slidable member 8 and then the three superimposed members of said assembly may be pushed back into the casing 7 to the extent desired against the opposition of spring 21. The pawl 12a is thus brought into engagement with the series 55 of ratchet shoulders formed by the apertures 25 in the terminal member 10, with the result that said pawl cooperates with said spring to maintain the slide 8 in its adjusted position. The extent to which said slide is inserted will, of course, determine the closeness of the fit of the bracelet upon the wrist of the wearer. When it is desired to remove the bracelet from the wrist, it is necessary only to pry up the projecting end portion 12 of the tongue 11 with a fingernail, or 70 otherwise, thus disengaging the pawl 12a from the apertures 25 and permitting the spring 21 to extrude from the casing the slidable member 8, together with the members 9 and 10 overlying it. The spring 21 may be made strong enough 75 to eject the foldover assembly with a sufficient

force not only to extrude the slidable member 8 but at the same time to throw the terminal members 9 and 10 out to the unfolded position shown in Fig. 7.

Although I have described my invention in detail and therefore utilized certain specific terms and language herein, it is to be understood that the present disclosure is illustrative rather than restrictive and that changes and modifications other than those shown may be resorted to without departing from the spirit or the scope of the subject matter claimed appended hereto.

What is claimed is:

1. In an extensible foldover extension for bracelets and the like, an elongated arcuate casing, a foldover extension comprising a bed plate member, a middle foldable member, and, a terminal foldable member, said middle and terminal foldable members being nested in said bed plate member and slidable into said casing in its folded over condition, a spring within said casing tending to extrude said extension therefrom, there being a longitudinally extending space within said casing alongside said inserted extension, and a resilient arched tongue anchored within said space and having a manually accessible end portion projecting from the end of said casing and furnished with a pawl, and ratchet shoulders carried by said terminal member in a cooperative relation to said pawl.

2. An elongated arcuated casing comprising an upper wall and a lower wall joined by vertical side walls; there being a mid-central rise extending longitudinally of said casing in the convex face of said upper wall; said upper wall having one end constructed for fastening with a bracelet chain; said lower wall being flanged to partially close the lower portion of the open end of said casing adjacent said constructed end; a foldover extension comprising a bed plate member, a middle foldable member, and a terminal foldable member, slidably mounted in said casing; said middle foldable member and said terminal foldable member being nested in said bed plate member; said terminal member being provided with a longitudinally extending series 35

of apertures; a resilient releasing arcuate tongue; said tongue having notches at one end, and a lift terminating in a pawl tooth at the other end; means to support said tongue in said mid-central rise at a point intermediate the ends of said casing with said notches detachably engaging the edge portion of said flange in such a manner that said tongue is pre-stressed between its points of support, whereby the free end of 55 said tongue through a lifting action may be flexed to release said pawl from one of said apertures incident to ejecting said foldover extension from said casing; stop means to limit the extrusion of said bed plate member; and means abutting the latter member to automatically eject said foldover extension from said casing upon release of said pawl from one of said apertures.

3. In a device of the kind described, an arcuate casing, a spring therein, a foldable bracelet extension comprising a bed plate member, a middle foldable member, and, a terminal foldable member, said middle and terminal foldable members being nested in said bed plate member and extrudable from said casing under the urge of said spring, ratchet shoulders carried by said terminal member, and a spring tongue mounted within said casing, said tongue having a protruding end portion forming a fingernail lift and an abutment 70

to engage the adjacent end of the casing, said protruding end portion being doubled over upon itself and having a projecting extremity which forms a pawl to cooperate with said shoulders.

5. 4. An elongated arcuated casing comprising an upper wall and a lower wall joined by side walls, said upper wall having one end constructed for fastening with a bracelet chain; said lower wall being flanged to partially close the lower portion 10 of the open end of said casing adjacent said constructed end; a foldover extension comprising a base member, a middle foldable member, and a terminal foldable member; said foldover extension being slidably mounted in said casing; said 15 middle and terminal foldable members being hinged one to the other to be folded together and nested in said base member; said terminal member being provided with a longitudinally

extending series of apertures; a resilient releasing arcuate tongue; said tongue being supported at one end of said casing, by the said flange of the said lower wall, with its upper convex face directed toward said upper wall; said tongue having a lift terminating in a pawl tooth at the other end; said lift being exposed at the end of said casing which is opposite said flange, said tongue through a lifting action being adapted to release said pawl from one of said apertures incident to ejecting said foldover extension from said casing; stop means to limit the extrusion of said foldover extension; and means operatively related to said foldover extension to automatically eject it from said casing upon release of 15 said pawl from one of said apertures.
